UNITED STATES PATENT OFFICE.

ARTHUR J. KITSON, OF ANN ARBOR, MICHIGAN.

ATTACHMENT FOR HAMMERS.

No. 800,305.

Specification of Letters Patent. Patented Sept. 26, 1905.

Application filed January 21, 1905. Serial No. 242,139.

To all whom it may concern:

Be it known that I, ARTHUR J. KITSON, a citizen of the United States, residing at Ann Arbor, in the county of Washtenaw and State of Michigan, have invented certain new and useful Improvements in Attachments for Hammers; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to new and useful improvements in attachments for hammers; and the object of the invention is to produce a buffer which may be applied to the head of a hammer and so arranged that it may be easily 20 and quickly applied and removed, said buffer affording means for preventing the marring of woodwork in which nails are driven by the hammer.

The invention consists, further, in various 25 details of construction, which will be herein-after fully described and then specifically defined in the appended claims.

My invention is illustrated in the accompanying drawings, in which—
30 Figure 1 is a perspective view showing my improved device as applied to the head of a hammer; and Fig. 2 is a central longitudinal section through the hammer-head, showing the device applied thereto.

35 Reference now being had to the details of the drawings by letter, A designates the head of a hammer of the usual construction, to which a handle B is secured.

E is a buffer which has a cylindrical portion adapted to fit over the hammer, as shown,

and a projecting strip F has a flat portion, whereby the device may be securely held to the end of the handle, as shown in the drawings, by means of screws. The buffer when applied to the hammer-head should project a 45 slight distance beyond the head of the hammer, whereby as a nail is driven by the hammer the parts about the wood through which the nail is driven will be protected from the blows of the hammer.

50 When it is desired to remove the buffer from the hammer, the projecting portion is first released from the handle, after which the cylindrical portion of the buffer may be easily drawn from off the head of the hammer.

55 While I have shown a particular detailed form of buffer, it will be understood that I may vary the shape of the same, if desired, without in any way departing from the spirit 60 of the invention.

Having thus fully described my invention, what I claim as new, and desire to secure by Letters Patent, is—

1. A buffer for hammers comprising a flexible sleeve adapted to fit over the head of a 65 hammer and provided with a projecting portion adapted to engage the handle of the hammer, as set forth.

2. A buffer attachment for hammers comprising a flexible sleeve adapted to fit over the head of a hammer and having a projecting portion, fastening means passing through 70 said projecting portion and engaging said handle, as set forth.

In testimony whereof I hereunto affix my 75 signature in presence of two witnesses.

ARTHUR J. KITSON.
